UNITED STATES PATENT OFFICE.

FRANKLIN J. PERKINS, OF WOBURN, MASSACHUSETTS, ASSIGNOR TO
VAUGHN-ROOD MACHINE COMPANY, OF PORTLAND, MAINE.

MACHINE FOR TREATING HIDES OR SKINS.

SPECIFICATION forming part of Letters Patent No. 746,144, dated December 8, 1903.

Application filed September 12, 1903. Serial No. 172,857. (No model.)

To all whom it may concern:

Be it known that I, FRANKLIN J. PERKINS, a citizen of the United States, residing in Woburn, in the county of Middlesex and State 5 of Massachusetts, have invented an Improvement in Machines for Treating Hides or Skins, of which the following description, in connection with the accompanying drawings, is a specification, like reference characters on the 10 drawings representing like parts.

This invention relates to a machine for treating hides, skins, and leather, and is especially adapted, among other uses, to be employed in the operations of putting out, un- 15 hairing, slating, &c.

The present invention has for its object to provide a simple and efficient machine for the purpose specified and one in which the entire surface of the skin may be treated at one 20 operation. For this purpose the machine is provided with operating-tools, preferably rolls or cylinders provided with helically-arranged blades, vanes, or working edges, which tools are arranged on opposite sides of the 25 path of movement of a table or support, such as now commonly employed in putting-out machines, and is further provided with a carrier for the hide or skin, which is movable in a path substantially at right angles to the 30 path of movement of the table and which carrier serves to present a portion of the hide or skin to the action of one of the operating tools or rolls, so that a portion of the hide or skin intermediate its ends is worked or 35 treated prior to the hide or skin being engaged by the movable table, which latter is brought into engagement with the hide or skin so that the treated portion of the hide or skin lies over the edge of the table and requires 40 no treatment while in this position, and the untreated portions of the skin are presented to the action of the rolls or tools lying on the opposite sides of the path of movement of the table, which tools or rolls treat the portions 45 of the hide or skin on the opposite sides of the table.

The invention is especially adapted for embodiment in machines employing a plurality of tables and commonly known as "serial-table machines," and provision is made for moving the carrier so that a fresh skin is

automatically presented to each table in succession. These and other features of this invention will be pointed out in the claims at the end of this specification.

55

Figure 1 is a front elevation, with parts broken away, of a machine embodying this invention; Fig. 2, a side elevation of the machine shown in Fig. 1 looking toward the left; Fig. 3, a vertical section of the machine 60 shown in Fig. 1, the section being taken on the line 3 3, Fig. 1; Fig. 4, a detail in side elevation and on an enlarged scale of the carrier to be referred to; Fig. 5, a detail in plan of a portion of the carrier shown in Fig. 4; 65 and Fig. 6, an end elevation of the carrier shown in Fig. 4 looking toward the right.

In the present instance the invention is shown as embodied in an upright serial-table machine provided with a plurality of work 70 supports or tables *a*, herein shown as three in number and which are pivotally secured to an endless carrier, comprising link chains *b*, which are passed about suitable sprocket-wheels *c d e*, mounted upon shafts *f g h*, supported by the uprights or side frames *i j*, which latter are erected upon a suitable base *k*. The sprocket-wheels *c d e* are preferably arranged substantially in the form of a triangle, with the sprocket-wheels *c e* in substantially the same vertical plane and which may be considered as the front side of the 75 machine, so that the tables or work-supports *a* are caused to move upward in a substantially vertical path at the front of the machine. 80

The machine is provided with working tools, which are arranged on opposite sides of the path of movement of the table as the latter moves vertically upward. These working tools may be of any desired construction 85 suitable for the particular work to be performed and are herein shown as rolls or cylinders provided with helically-arranged blades, vanes, or working edges. The working cylinders or rolls on each side of the path of movement of the table are located or arranged in substantially the same vertical plane, and in the present instance I have shown the machine as provided with two rolls or cylinders *m n* on one side of the path of 90 movement of the table and three rolls or cylinders *o p q* on the opposite side of the path 95 of movement of the table.

of movement of the table. Each of the rolls referred to is provided with helically-arranged blades or working edges *r*.

The present invention has for its primary object to effect a working of the entire surface of the hide or skin by the rolls or tools located on opposite sides of the path of movement of the table, and to this end provision is made for causing a portion of the hide or skin intermediate its ends to be worked by one of the tools or rolls lying on one side of the path of movement of the table and thereafter to cause the remaining portion of the hide or skin to be worked while lying against the opposite sides of the table by the tools or rolls located on the opposite sides of the path of movement of the table. One means for effecting this result is herein shown and will now be described. The machine is provided with a carrier for the untreated hide or skin, which carrier is movable in a path substantially at right angles to the path of movement of the table, and as herein shown comprises a substantially V-shaped stationary piece or member 10 and a yielding member 12, both of which are secured to a supporting-frame comprising side pieces 13, which slide upon suitable ways or tracks 14, secured to the side frames of the machine and extended in a substantially horizontal direction from the front to the rear of the machine.

The movable member 12 is made sufficiently long to cause a hide or skin placed over it to be brought into engagement with one of the rolls or tools located on one side of the path of movement of the table *a*, and in the present instance the movable member 12 presents the hide or skin to the action of the roll or tool *q*, which puts out, unhairs, or otherwise treats a portion of the hide or skin intermediate its ends. The carrier is then moved so as to shift the position of the skin with relation to the path of movement of the table and to bring the portion of the hide or skin which has been treated by the roll *q* into the path of movement of a table *a*, which latter on its upward movement passes between the members 10 12 of the carrier and engages the hide or skin, so that the portion previously treated by the roll *q* lies over the edge of the table. The upward movement of the table lifts the hide or skin from its carrier and presents the untreated portions to the action of the rolls located on opposite sides of the path of movement of the table, so that the side of the hide or skin on one side of the table may be treated by the rolls *m n* and on the other side by the rolls *o p*, and, if desired, also by the roll *q*. In this manner the entire surface of the hide or skin may be treated in one operation by working tools which are located on opposite sides of the path of movement of the table. In fact, by means of this invention the rolls or tools now commonly employed in machines of this class for treating or working only the portions of the hide or skin on opposite sides of the table are enabled to effect the working

of the entire surface of the hide or skin. The member 12 of the carrier may be made yielding to compensate for uneven thickness 70 of the hide or skin, and the roll *q* may be mounted in fixed bearings, or vice versa. In the present instance the roll *q* is shown as mounted in fixed bearings and the member 12 as yielding, being acted upon by the spring 75 15, the tension of which may be adjusted by the screw 16.

The rolls *m n o p* may be yieldingly supported, which may be effected in any suitable manner, and in the present instance the rolls 80 *m o* are shown as mounted in levers 18 19, pivoted at 20 21 to a stationary part 22 of the framework and having their free ends connected by the links 23 24 25 to a lever 26, pivoted to the frame of the machine and provided with a weight 27, which may be adjustable on the lever to regulate the pressure of the rolls *m o* on the hide or skin. The rolls *n p* are similarly supported, being sustained by levers 30 31, mounted on the pivots 20 21 90 and having their free ends connected by the links 32 33 34 to the lever 35, provided with the weight 36. The movement of the rolls or tools toward the path of movement of the table *a* may be limited or arrested in any 95 suitable manner. The carrier for the hide or skin may be reciprocated in any suitable manner, and in the present instance I have shown one means for effecting this result. For this purpose the carrier is provided with 100 arms 38 at its opposite sides, which carry rollers 39, the latter engaging cams shown as grooves 40 in the side of disks 41, mounted on a shaft 42, which is suitably driven, and for this purpose the said shaft is provided with 105 a gear 43, which meshes with a gear or pinion 44 on the shaft of the sprocket-wheel *d*, and the said cam is suitably shaped and so timed with relation to the movement of the endless carrier for the hide or skin so as to present a hide or skin to each table in succession. 110

The rotatable parts of the machine are driven from a main shaft 45, provided, as shown, with fast and loose pulleys 46 47. The 115 main shaft 45 is provided with a sprocket-wheel 48, which is connected by the link chain 49 with the sprocket-wheel 50 on a shaft 51, supported at the top of the side frames *i j*. The shaft 51 is provided with pinions 120 52, which mesh with gears 53 on the sprocket-wheel shaft *f*. The shaft 51 is also provided with sprocket-wheels 54 55, (see Fig. 1,) which are connected by link chains 56 57 with sprocket-wheels 58 59 on the work rolls or 125 cylinders *o p*. The work-rolls *m n* are driven by link chains 60 61 from a counter-shaft 62, provided with a gear 63, which meshes with and is driven by a suitable pinion (not shown) on the main shaft 45. The work-roll *q* is 130 driven by the link chain 65 from the main shaft 45.

The members 10 12 of the carrier support the sides of the hide or skin when the lat-

ter is moved upward by the table, and by reference to Fig. 3 it will readily be understood that the said members hold the sides of the hide or skin away from the table, and thereby enable the rolls or tools to treat the portions of the hide brought into engagement with them without danger of plaiting, cutting, or otherwise injuring the hide or skin, owing to the fact that the sides of the hide or skin, which is usually wet, are not allowed to come in contact with the table until at or about the time the hide or skin is presented to the action of the operating-rolls. In other words, the members 10 12 serve to hold the free ends or portions of the hide or skin away from the sides of the table and afford opportunity for the sides of the hide or skin to flow or move under the action of the operating-tools in substantially the same way as the hide or skin is now held by operators away from the table in some forms of machines of this class.

In the operation of the machine herein shown the carrier is moved by its cams in the direction indicated by the arrow 70 a sufficient distance to enable the operator to readily place a hide or skin over the member 12 and preferably so that substantially the central portion of the hide or skin is between the member 12 and the member 10 of the carrier, which is then moved in the direction opposite to that indicated by the arrow 70 by the cams, and the portion of the hide or skin resting against the inner surface of the member 12 is engaged with the operating tool or roll *q*, which treats or works the portion of the hide or skin between the roll *q* and the member 12. While the roll *q* is working the hide or skin, as described, the circular portion of the cam-groove between the points 71 72 is in engagement with the roller 39 and the carrier is at rest. At or about the time the roll *q* has treated or worked the portion of the hide between it and the member 12 the carrier commences its movement toward the front of the machine and the portion of the skin treated by the roll *q* is moved across the path of movement of the table *a*, which on its upward movement is brought into engagement with the under surface of the hide or skin, the said table passing between the members 10 12 and engaging the hide or skin, so that the portion treated by the roll *q* lies over or on the upper edge of the table and extends on both sides of the latter a sufficient distance to be engaged by the rolls *n p m o*, which treat or work the portions of the hides or skins on opposite sides of the table as the latter is moved or carried between said rolls. When the table, with a hide thereon, has passed upward, so as to clear the member 12, the carrier continues its movement toward the front of the machine and is brought into position to receive another hide or skin. The carrier remains at rest in what may be termed its "receiving" position by the circular portion of the cam-groove between the points 74 75.

I may prefer to employ the rolls or working tools *o p* in addition to the roll *q*; but I do not desire to limit my invention in this respect, as the roll *q* alone and one or both of the rolls *m n* are sufficient to effectively work or treat the entire surface of a hide or skin.

I have herein shown one form of carrier and mechanism for reciprocating the same; but I do not desire to limit my invention to the particular form of carrier and its operating mechanism herein shown. I have herein shown the rolls or tools *m n o p* mounted in levers; but I do not desire to limit my invention to this particular manner of supporting said tools.

The member 12 of the carrier is preferably made yielding, as shown in Figs. 4 to 6, inclusive, in which the said member is shown as fast on a rock-shaft 80, supported in the side frames 13 of the carrier and provided at its opposite ends with cranks or arms 81, which have the upper ends projected over the side frames 13 and engaged by the springs 85 15, which normally force the cranks 81 upward until arrested by a suitable stop, shown as a nut 82 on the end of the screw or bolt 16.

I claim—

1. In a machine of the character described, in combination, a table or support for the hide or skin, means to move it, operating-tools located on opposite sides of the path of movement of the said table or support, and a carrier for the hide or skin coöperating with one of said tools to effect working of a portion of said hide or skin prior to the engagement of the hide or skin with said table or support, substantially as described.

2. In a machine of the character described, in combination, a table or support for the hide or skin, operating-tools located with relation to said table or support to work portions of the hide or skin on opposite sides thereof, one of which devices is bodily movable with relation to the other, and a carrier for the hide or skin movable toward and from said operating-tools and coöperating with one of said tools to effect working of a portion of the hide or skin intermediate its ends, substantially as described.

3. In a machine of the character described, in combination, a substantially flat table or support for a hide or skin, means to move it, operating-tools located on opposite sides of the path of movement of said table or support, a second support for the hide or skin movable substantially at right angles to the path of movement of the said table and coöperating with one of said operating-tools to effect working of a portion of the hide or skin while on said second support, substantially as described.

4. In a machine of the character described, in combination, a table or work-support, means to move said table in a substantially vertical path, operating-tools located on opposite sides of the path of movement of said table or work-support, a yielding support over

- which a hide or skin is adapted to be placed, movable toward and from the path of movement of said table, and means for treating the hide or skin while on said yielding support, substantially as described.
5. In a machine of the character described, in combination, a table or work-support, means to move said table in a substantially vertical path, operating-tools located on opposite sides of the path of movement of said table or work-support, a carrier for the hide or skin movable toward and from the path of movement of said table to place the hide or skin on the said carrier into position to be removed from said carrier by the said table or support, means to move said carrier, and means to treat the hide or skin while on the carrier, substantially as described.
6. In a machine of the character described, in combination, a table or work-support, means to move it, a carrier for a hide or skin movable toward the path in which said table is moved to place the hide or skin into position to be removed from said carrier by said table, means to move said carrier, means for treating the hide or skin while on said carrier, and means for treating the hide or skin while on said table, substantially as described.
7. In a machine of the character described, in combination, a table or work-support, means to move it, a carrier for a hide or skin movable toward the path in which said table is moved to place the hide or skin into position to be removed from said carrier by said table, and provided with a yielding member over which a hide or skin is adapted to be placed, means to move said carrier, and means for treating the hide or skin while on the yielding member of said carrier, substantially as described.
8. In a machine of the character described, in combination, a table or support for the hide or skin, means to move it, operating-tools located on opposite sides of the path of movement of said table, and means on opposite sides of the path of movement of said table to support the free ends of the hide or skin away from the sides of said table, substantially as and for the purpose specified.
9. In a machine of the character described, in combination, a table or support for the hide or skin, means to move it, operating-tools on opposite sides of the path of movement of the said table, a reciprocating carrier for the hide or skin movable at an angle to the path of movement of said table, and a cam to effect reciprocation of said carrier, substantially as described.
10. In a machine of the character described, in combination, an endless carrier, a plurality of tables secured thereto, operating-tools located on opposite sides of the path of movement of said tables, a device to support the hide or skin movable toward and from the path of movement of the tables and co-operating with said operating-tools to effect treatment of the hide or skin thereon and co-operating with said tables to place the hide or skin in position to be removed from it by a table as the latter is moved by or past the said device, substantially as described.
11. In a machine of the character described, in combination, a table or support for a hide or skin, means to move it, and a carrier for the hide or skin movable laterally with relation to the path of movement of said table and co-operating with the latter to place the hide or skin in position to be removed from said carrier by the said table as the latter is moved by or past the said carrier, and operating-tools for treating the said hide or skin, substantially as described.
- In testimony whereof I have signed my name to this specification in the presence of two subscribing witnesses.
